UNITED STATES PATENT OFFICE.

LEE DE FOREST, OF NEW YORK, N. Y.

AEROPHONE.

No. 836,072.

Specification of Letters Patent.

Patented Nov. 13, 1906.

Original application filed December 11, 1905, Serial No. 291,222. Divided and this application filed December 22, 1905.
Serial No. 292,922.

To all whom it may concern:

Be it known that I, LEE DE FOREST, a citizen of the United States, and a resident of New York, in the county of New York and State of New York, have invented a new and useful Improvement in Aerophones, of which the following is a specification.

My invention relates to wireless-telephone systems for transmitting and receiving vocal or other sounds, including articulate speech, by electromagnetic waves.

The object of my invention is to produce a wireless telephone or aerophone in which a resistance device is varied by and in accordance with the air vibrations accompanying vocal or other sounds, and thereby correspondingly varies the amplitude of continuously-transmitted trains of electromagnetic waves and in which said waves so varied as to amplitude develop in a receiving system electrical oscillations correspondingly varied, and thereby correspondingly vary the amplitude of the current in a telephone-receiver.

My invention may best be understood by having reference to the drawings which accompany and form a part of this specification and which illustrate conventionally several devices and systems of circuits whereby my invention may be carried into effect.

In the drawings, Figures 1, 2, 3, and 4 are diagrams of aerophone transmitting systems.

In Figs. 1, 2, and 3, G is a high-frequency alternating-current generator producing at least seven hundred and fifty cycles per second, and preferably the frequency of said generator should be as high as can conveniently and commercially be produced.

In Figs. 1 and 3 the generator G energizes the oscillating circuit C S L directly, although, as shown in Fig. 2, the transformer I may be interposed between said circuit and generator for appropriately varying the difference of potential impressed upon the condenser C by the generator. By means of the adjustable connections of the oscillating circuit and antenna A with the inductance L the natural periods of said antenna and circuit may be brought into agreement.

The element shown in the several figures, as K K' K'' K''', represents a resistance device of any suitable character which is adapted to be controlled by the vibrations of the air accompanying vocal or other sounds, including articulate speech.

In Fig. 1, K is represented as a carbon microphone, preferably of the kind used in circuits carrying currents of amplitudes large compared to the amplitudes of the currents which are modified by the usual granular carbon transmitter in ordinary wire telephony.

In Fig. 2, K' is a flame made more conducting by the addition of sodium salts or other suitable salts.

In Fig. 3, K'' is a spark-gap. In Fig. 4, K''' is an arc of the type investigated by Simon (Wiedemann's Annalen, Vol. 64, p. 233, 1898) and Duddell (Journal of the Institution of Electrical Engineers, December 13, 1900, p. 232) and known as the "speaking-arc."

The variable-resistance devices may best be placed, as shown in Figs. 1, 2, and 3, at points in the system near the earth connection, because at such points the current in the system is near its maximum value and the potential is near its minimum value. Accordingly the said resistance devices are less liable to be injured or rendered inoperative by having excessive potentials impressed upon their terminals and are enabled to produce a far greater variation in the amplitude of the currents in the antenna, and hence in the amplitude of the radiated waves, by slight changes in resistance than if they were located between the inductance L and the top of the antenna. While the location of the variable-resistance devices in the antenna system near the earth connection, as shown in Figs. 1, 2, and 3, is preferred, I do not limit myself to a variable-resistance transmitter so located, for, as shown at K''' in Fig. 4, said resistance device or transmitter may be so located as to be common to the antenna and the closed oscillating circuit. In other words, I do not limit myself to any particular variable-resistance transmitter or to any particular location or position thereof in the system, but consider any suitable transmitter operatively associated with the system, as set forth in the claims, within the scope of my invention when used to vary the amplitude of electrical oscillations produced by a continuously-operating train of sparks having a spark-gap frequency higher than the frequency of the more essential vibrations accompanying speech as, for example, fifteen hundred pulsations per second.

With all the variable-resistance devices any suitable sound-amplifying and concen-

trating device may be used—such, for example, as the megaphone M (shown in Figs. 2, 3, and 4) or the well-known compressed-air device F (shown in Fig. 3), in which the diaphragm V of the megaphone operates on a reducing-valve to vary the flow of air from the tank F through the nozzle G'.

- The operation is as follows: In Figs. 1, 2, and 3 the generators G charge the condensers 10 C a sufficient number of times per second to create in the oscillating circuits S C L electrical oscillations having a spark frequency higher than the more essential frequencies which make up the complex voice-waves, 15 and said oscillations result in the radiation from the antenna of electromagnetic waves having similar spark frequency. The electromagnetic waves develop oscillations in a receiving - antenna, thereby producing a 20 current varying at a rate equal to the spark frequency of the transmitted waves. The effect of said varying current on the telephone-receiver depends, of course, upon the rate of its variation. If desired, this rate 25 may be made to exceed the limit of response of the telephone-diaphragm, especially if the speaking-arc circuits of Fig. 4 are employed at the transmitting-stations; but such rapid variation is not necessary, all that is necessary, 30 as in the case of the well-known Gibboney or Hutin-Leblanc alternating-current systems of telephony, that the rate of current variation in telephone-circuit be higher than the most important frequencies 35 occurring in telephonic transmission, in which case the telephone will produce a note having the pitch equal to the spark frequency employed at the transmitting-station. In either case any variation in the amplitude 40 of the currents in the local telephone-circuit will produce a corresponding variation in the sound emitted by the telephone, and therefore if by any of the variable-resistance transmitters shown herein or by any other 45 means the amplitude of the transmitted waves be modified in a manner corresponding to the voice-waves the telephone will reproduce sounds simulating those produced at the transmitting-station.
- 50 In Fig. 4 the direct-current generator G' creates in its circuit C L' K''' electrical oscillations the frequency of which may be regulated in the well-known manner by regulating the electrostatic time constant of the 55 condenser-charging circuit. In Fig. 4 the voice-waves concentrated by the megaphone M, which is directed toward the arc K''', produce the desired current variations in the antenna.
- 60 This application is a division of my application, Serial No. 291,222, filed December 11, 1905.

It will be obvious that many other devices and systems may be devised for varying by 65 and in accordance with speech-waves the

amplitude of continuously-transmitted trains of waves having a spark-gap frequency higher than the more essential frequencies accompanying speech, and therefore I do not wish to limit my invention to the particular embodiments thereof herein shown and described.

I claim—

1. An aerophone comprising means for continuously transmitting trains of electromagnetic ether waves having a spark frequency higher than the more essential frequencies accompanying speech-waves, and means located in the antenna system between the earth connection thereof and the point at which energy is supplied thereto whereby said waves may be modified in accordance with speech-waves. 7

2. In an aerophone, an oscillating circuit including a condenser and a spark-gap, 85 means for continuously developing in said circuit electrical oscillations having a spark frequency higher than the more essential frequencies accompanying speech-waves and means located in the antenna system between the earth connection thereof and the point at which energy is supplied thereto, whereby said waves may be modified in accordance with speech-waves. 90

3. An aerophone comprising means for 95 continuously transmitting trains of electromagnetic ether waves having a spark frequency higher than the more essential frequencies accompanying speech-waves, and a resistance device located in the antenna system between the earth connection thereof and the point at which energy is supplied thereto whereby said waves may be modified in accordance with speech-waves. 100

4. In an aerophone, an oscillating circuit 105 including a condenser and a spark-gap, means for continuously developing in said circuit electrical oscillations having a spark frequency higher than the more essential frequencies accompanying speech-waves and a resistance device located in the antenna system between the earth connection thereof and the point at which energy is supplied thereto whereby said oscillations may be modified in accordance with speech-waves. 110

5. In an aerophone, means for developing 115 electrical oscillations having a relatively high spark frequency, means located in the antenna system between the earth connection thereof and the point at which energy is supplied thereto whereby said oscillations may be modified in accordance with sound-waves, and means for converting said oscillations so modified into electroradiant energy. 120

6. In an aerophone, means for developing 125 electrical oscillations having a relatively high spark frequency, a resistance device located in the antenna system between the earth connection thereof and the point at which energy is supplied thereto whereby said os- 130

cillations may be modified in accordance with sound-waves, and means for converting said oscillations so modified into electroradiant energy.

5. 7. In an aerophone, a transmitting-antenna means for developing electrical oscillations therein, and means in said antenna and located between the earth connection thereof and the point at which energy is supplied thereto whereby said oscillations may be varied.

15. 8. In an aerophone, a transmitting-antenna, means for developing electrical oscillations therein, and means in said antenna and located between the earth connection thereof and the point at which energy is supplied thereto whereby said oscillations may be varied in accordance with vocal sounds.

20. 9. In an aerophone, a transmitting-antenna, means for developing electrical oscillations therein, and a resistance device in said antenna and located between the earth connection thereof and the point at which energy is supplied thereto whereby said oscillations may be varied.

25. 10. In an aerophone, a transmitting-antenna, means for developing electrical oscillations therein, and a resistance device in said antenna and located between the earth connection thereof and the point at which energy is supplied thereto whereby said oscillations may be modified in accordance with vocal sounds.

30. 11. In an aerophone, means for developing electrical oscillations, a spark-gap located in the path of said oscillations, a source of compressed gas for modifying the resistance of said gap to the oscillations passing across it, and means controlled by voice-waves for 35 controlling the effect of said compressed gas on the resistance of said gap.

40. 12. In an aerophone, a transmitting-antenna having a definite natural period, means for impressing thereon electrical oscillations having the same period and having a spark 45

frequency higher than the more essential frequencies accompanying speech-waves, and means in said antenna and located between the earth connection thereof and the point at which energy is supplied thereto whereby 50 said oscillations may be modified in accordance with speech-waves.

13. In an aerophone, a transmitting-antenna having a definite natural period, means for impressing thereon electrical oscillations 55 having the same period and having a spark frequency higher than the more essential frequencies accompanying speech-waves, and a resistance device in said antenna and located between the earth connection thereof and 60 the point at which energy is supplied thereto whereby said oscillations may be modified in accordance with speech-waves.

14. In an aerophone, a transmitting-antenna having a definite natural period, 65 means for impressing thereon electrical oscillations having the same period and having a spark frequency higher than the more essential frequencies accompanying speech-waves, a resistance device consisting of a 70 spark-gap of constant length arranged in the path of said oscillations, and means associated with said spark-gap whereby said oscillations may be modified in accordance with speech-waves.

75. 15. In an aerophone, a transmitting-antenna, an oscillation-circuit, means operatively associating said circuit with said antenna, and a resistance device located in said antenna below said means whereby the oscillations in said antenna may be modified in accordance with vocal sounds.

In testimony whereof I have hereunto subscribed my name this 18th day of December, 1905.

LEE DE FOREST.
